UNITED STATES PATENT OFFICE.

DWIGHT S. MORROW, OF MILAN, OHIO.

PLURAL LIQUID-DISTRIBUTING SYSTEM.

Application filed September 8, 1925. Serial No. 55,058.

This invention, as indicated, relates to a plural liquid distributing system and an automatically operated distributing valve for use therewith.

5 The subject matter in this application is an improvement over my Patent No. 1,490,179, granted April 15, 1924, wherein a single valve casing was provided and a multi-piston distributing valve made up of two 10 similar sections bolted together and forming one unitary sliding member was operatively engaged therein.

One of the principal objects of the present invention is the provision for a casing 15 having a plurality of compartments instead of a single compartment casing, one of said compartments serving as the inlet chamber of either of the fluids to be pumped, for example hard or soft water, a central chamber 20 serving as a governor chamber and the other chamber serving as the liquid distributing means to the lines leading to the respective receiving tanks.

Another object of the invention is the provision of multiple chambers and separate 25 valves for each of the inlet and discharge lines.

A further object of the invention is to provide a positive closing of each port independently of the associated ports.

Another object of the invention is to provide for a two stage operation of the governor valves so that the pump may empty out the water of the character in transit before 35 shifting to the water supply of the other character.

A further object of the invention is to improve the mechanical construction of the apparatus whereby the small tubular passage ways are dispensed with and straight passage ways are provided directly between the several chambers of the casing.

A still further object of the invention is the provision of a check valve for each suction line, thus preventing accidental siphoning 45 of water from one source of supply to the other, or from a higher to a lower water level.

It is also in view that in place of delaying 50 the valve action until the pump can clear of the water of the kind previously operated on before commencing on the water supply of the other character, that a complete discharge of said water to a waste line may be adopted.

Other and further objects of the invention

will appear in the course of the following description. To the accomplishment of the foregoing and related ends, said invention, then, consists of the means hereinafter fully 60 described and particularly pointed out in the claims.

The annexed drawings and the following description set forth in detail certain mechanism embodying the invention, such disclosed 65 means constituting, however, but one of various mechanical forms in which the principle of the invention may be used.

In said annexed drawings:

Fig. 1 is a diagrammatic view showing a 70 plural liquid distributing system; Fig. 2 is a top plan view of the automatically operated distributing valve; Fig. 3 is a view of the valve shown in Fig. 2 as seen from the right hand side, and Fig. 4 is a longitudinal 75 vertical sectional view of the distributing valve shown in Figs. 2 and 3.

As is clearly shown in Fig. 1 of the drawing a pump 1 of standard construction is operated by a suitable motor 2 and is provided with an inlet line 3 and a discharge line 4. An air dome 5 may also be provided to provide continuous flow. The inlet and discharge lines communicate with the automatically operated distributing valve 6 80 through suitable ports which are provided with nipples 7, 8, and other ports provided with nipples 9, 10, 11 and 12 in said valve communicate respectively through a line 13 with a hard water tank, through a line 14 85 with a cistern, through a line 15 with a soft water tank, and through a line 16 with a well or other source of hard water.

The valve construction is more particularly shown in Fig. 4, where it will be noted 90 that the valve casing is provided with an upper or discharge chamber 21, an intermediate chamber 22, and the lower or inlet chamber 23. Each of said chambers is of cylindrical form, the upper and lower chambers being preferably of larger diameter than the intermediate chamber. The chambers are all of equal length, and the ends thereof are closed and may be formed from an integral casting. The end walls of said 100 chambers comprise end plates 24, 25, which may be provided with ears 26, through which said plates may be secured to the end flanges 27, 28 by screws or other fastening devices. The inlet and discharge lines from the pump are connected with the valve casing by means of the nipples 7, 8 respec-

2

tively, which are provided upon the right hand side of the valve casing and surround the ports 31, 32 respectively. Annular valve seats 33, 34, 35, 36 are provided at either side respectively of the inlet and discharge ports 31, 32. In the lower wall of the intermediate chamber at a central point, a passage way 37 between said intermediate chamber and the lower chamber is provided, and similar passage ways 38, 39 are provided through the bottom wall of said intermediate chamber at points adjacent the end walls of the casing. A pair of similar passage ways 41, 42 are provided between the intermediate chamber and the upper chamber. Said last mentioned passage ways are spaced a greater distance inwardly from the end walls of said casing than the passage ways 38, 39 for a purpose which will presently appear. The upper wall of the intermediate chamber is also provided with inclined passage ways 43, 44, which are shown in Fig. 3 and may each be formed by drilling angularly disposed holes 45, 46 through the upper walls of said intermediate chamber, said holes meeting. Said holes clear the passage ways 41, 42 and meet at an angle within the upper wall of the intermediate chamber. Said passage ways 43, 44 lead from a point outwardly from the valve seats 33, 34 respectively, and incline downwardly to a point closely adjacent the ends of the intermediate chamber at which point they communicate therewith. In the lower chamber a horizontal valve shaft 51 is provided which carries at its outer ends the working heads 52, 53, against which outwardly-faced leather cup washers 54, 55 are seated. At an intermediate point upon said shaft, a pair of disk valves 56, 57 are slidingly supported, said valves being adapted respectively to seat against the inner faces of the valve seats 35, 36 heretofore referred to. An expansion coil spring 58 is positioned to surround said shaft with its ends bearing against the respective inner faces of said valve disks. The valve shaft 51 is provided centrally with an enlargement 59 providing shoulders at either end which are adapted to bear against the respective valves as said shaft is moved horizontally. The valve disks 56, 57 are preferably each composed of thin sheet metal plates upon the outer face of which a disk of rubber is cured.

Within the upper chamber a horizontally extending shaft 61 is provided, a central portion of said shaft being of reduced diameter, and the ends 62, 63 thereof being of enlarged diameter and providing shoulders 64, 65 of a length suitable to cooperate with valve disks presently to be described. The outer ends of said shaft are provided with working heads, each preferably comprising a metal plate 66 upon opposite sides of which

a pair of reversely faced leather cup washers 67, 68 are secured. Upon the reduced central portion of the shaft, a pair of valve disks, 71, 72 are slidingly mounted. Said valve disks each comprise a metal plate against the inner face of which a rubber disk is secured. Said valve disks are adapted to engage respectively against the outer faces the valve seats, 33 and 34 heretofore described. Expansion coil springs, 73, 74 are positioned respectively about the enlarged end portions of the shaft and their ends bear against the working heads of the shaft, and the adjacent valve disks respectively.

Within the intermediate chamber 22 a longitudinally positioned shaft 81 is provided. Said shaft is of somewhat greater length than the shafts 51 and 61 heretofore described and is provided at its ends with working heads 82, 83, against the outer faces of which outwardly turned cup washers 84, 85 respectively are positioned, said shaft and the working heads thereon comprising the governor valve mechanism of the apparatus.

In addition to the structural elements heretofore described, the apparatus will be provided with standard means for automatically controlling the pumping unit. Such control devices are well known in the art, and serve to cut off the pumping unit when both tanks are full, and serve to start the pumping unit when the pressure in either of said tanks falls below a predetermined amount.

The operation of the apparatus is as follows:

The pressure in the hard water tank is at all times brought to bear upon the governor head 82 in the intermediate chamber through the passageway 44 and the pressure in the soft water tank is also at all times brought to bear on the governor head 83 through the passageway 43.

When the pressure in the hard water tank is less than that in the soft water tank and the parts of the distributing valve are in the position shown in Fig. 4 of the drawing, if the pump be set to operating by suitable means, automatic or otherwise, it will produce suction in the inlet line 31, water will be drawn from the well through the line 16 into the right hand side of the lower chamber 23, and will force the valve 57 to the left. The water will flow through the port 31 and line 3 into the pump 1, and thence will be discharged through the line 4 and port 32 into the upper chamber, forcing the disk 71 to the left and thence passing through the line 13 into the hard water tank.

When the pressure in the hard water tank is relatively greater so as to overbalance the pressure from the soft water tank, the governor valve will move to the right, the head 82 passing the port 38 and stopping momentarily at such point, while the pressure is escaping from behind the governor head 82

through the port 38 and into the lower chamber, where it operates against the head 52 moving the same to the right, and bringing the shoulder of the enlargement 59 tightly against the valve disk 57, thus shutting off the well water from the suction line and permitting the suction to move the valve 56 inwardly and thus opening the passage way for the cistern water through the line 14 to enter the inlet port 31. At this time the pressure on the governor head 82 will be increased and will force the same further to the right until it passes the port 41 where it again stops, while pressure on the head 66 in the upper chamber is built up and the valve shaft 61 moves to the right until the shoulder 64 bears against the valve disk 71, thus closing the well water discharge line, and permitting the cistern water control valve 72 to be forced open, and the cistern water to be supplied to the soft water tank through the line 15.

The delayed operation of the several valves just described is intended to permit the pump to empty all of the liquid being handled in order that no mixture of hard and soft water in the tanks will occur, if such are the fluids being utilized in the system. With an ordinary installation, it has been found that by allowing a period of five seconds between the time of the closing of the suction valve for the hard water and the closing of the discharge valve therefor, the pump will be practically free of the hard water before commencing to operate upon the soft water supply.

After the valve operations described have taken place, the governor head 82 moves further to the right due to the increased pressure thereon until the governor head 83 comes in contact with the end wall 25. Said head 83 is then forced past the valve ports 42 and 39, and the pump suction is then exerted through the ports 37 and 42, relieving all back pressure on the heads 53 and 66.

When the pressure in the soft water tank reaches a predetermined amount, preferably 8 pounds more than the pressure in the hard water tank, the governor heads 83 and 82 will be moved to the left and the various valves will be shifted so as to resume their original position or the positions disclosed in Fig. 4. The springs 73 and 74 serve to normally keep the disk valves against their seats, which prevents any surging of water from the higher to the lower pressure tank. When the automatic control of the pump starts the mechanism, the force of the liquid entering through the discharge port 32 will be sufficient to operate the valve 71.

It is to be noted that the disk valves 71 and 72 are loosely engaged upon the shaft 61, which allows a slight amount of water to pass said valve disks and thus, at all times, maintain enough pressure on the

pump valves to prevent their leakage and a constant starting and stopping of the pump which would follow the failure to maintain such pressure. Such slight leakage through the valve disk only takes place in the valve which is not abutted by either of the adjacent shoulders 64 and 65 on the shaft 61, inasmuch as the shoulder makes a ground joint to fit with the adjacent valve plate and prevents the passage of liquid through the valve disk engaged thereby.

The valve disks 56 and 57 are also slidably mounted upon the head supporting shaft 51 and the spring 56 bearing thereagainst serves to have said valve disks function as check valves on both suction lines. This prevents any accidental siphoning action, which experience has shown at all times occurs between a cistern and a well where the water level in the well is considerably lower than the water level in the cistern. In the absence of such construction, such action might take place during the time of the shifting of the valve, particularly when the pump is idle and the pressure in the tanks change in amount sufficient to shift the valves without starting the pump.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A device of the character described, having in combination a distributing valve, means connecting said valve with two sources of fluid supply of different character, and automatic means for controlling the ports of said valve to change from one fluid supply to another, while preventing intermixture.

2. A device of the character described, having in combination a distributing valve, means connecting said valve with two sources of fluid supply of different character, means for discharging said fluid supply through said valve to separate storage structures, means for connecting a pressure means with said valve for forcing fluid through the same and means for controlling the ports of said valve so as to admit fluid of only one kind at a time and to change to fluid of a different kind, and means for delaying the opening of the discharge ports until the fluid forcing means has been cleared for the fluid being handled.

3. A device of the character described having in combination a pair of fluid transmission lines connected respectively with a source of fluid supply and a storage structure, each of said lines being adapted for the handling of different fluids, a distributing

valve interposed in said lines, means in said valve responsive to the differential pressures in said supply lines for opening or closing one of said lines, and means associated with 5 said last named means to permit the clearing of the pumping unit of the fluid supply being handled prior to operating upon the other fluid supply.

4. In a device of the character described, 10 a casing having connections for different fluids, a valve stem in said casing, a plurality of valves on said stem movable thereby but also capable of limited independent movement, and means for operating said 15 valves by fluid pressure.

5. In a device of the character described, 20 a casing having connections for different fluids, a valve stem in said casing, a plurality of valves on said stem, means on said 25 stem for engaging each valve for a certain extent of movement, resilient means for engaging each valve for a certain extent of movement, and means responsive to fluid pressure for controlling the operation of said valves.

6. In a device of the character described, 30 a casing having an inlet chamber and connections for different fluids, a valve stem in said casing, a plurality of valves on said stem movable thereby, means causing said 35 valves to act independently as check valves, and a control member responsive to fluid pressure for determining the position of said valve stem.

35 7. In a device of the character described a distributing valve comprising a casing having an intake and a discharge chamber, an automatic control chamber disposed between

and parallel to said first named chambers, a pair of valve controlled connections in 40 one of said chambers connected respectively with a hard water and soft water storage tank connections in the second mentioned chamber respectively, with a source of hard water and a source of soft water supply, 45 valves controlling said respective sources of supply and means disposed in said intermediate chamber for operating said valves by fluid pressure.

8. In a device of the character described a 50 distributing valve comprising a casing having an intake and a discharge chamber, an automatic control chamber disposed between and parallel to said first named chamber, a pair of valve controlled connections in one 55 of said chambers respectively with a hard water and soft water storage tank connections in the second mentioned chamber respectively, with a source of hard water and a source of soft water supply, valves 60 controlling said respective sources of supply, a pair of differential valves in each of said water intake and water discharge chambers, ports for transmitting the pressure of said 65 respective water tank lines to the central control chamber, means responsive to the pressure transmitted through said ports in said central control chamber, and other ports placed in communication with said central 70 control chamber through the operation of said control means, said last named ports communicating with the water supply chamber and changing the pump connections thereto.

Signed by me, this 4 day of Sept., 1925.
DWIGHT S. MORROW.
